UNITED STATES PATENT OFFICE.

PHOEBE A. GREEN AND ANDREW W. GREEN, OF TORONTO, ONTARIO, CANADA; SAID
PHOEBE A. GREEN ASSIGNOR TO SAID ANDREW W. GREEN.

FLOOR WAXING AND POLISHING APPARATUS.

Application filed January 29, 1923. Serial No. 615,581.

To all whom it may concern:

Be it known that we, PHOEBE A. GREEN and ANDREW W. GREEN, both of the city of Toronto, in the county of York, Province 5 of Ontario, Canada, subjects of the King of Great Britain, have invented certain new and useful Improvements in Floor Waxing and Polishing Apparatus, of which the following is a specification.

10 This invention relates to floor waxing and polishing apparatus and more particularly to that type in which a plurality of floor finishing tools including a brush and a waxer pad are rotatably and interchangeably carried on a carriage and rotated by an electric motor and our object is to provide means for limiting the spread of the bristles of the brush; another object is to construct the apparatus so that it is better 15 adapted to brush an uneven floor, a further object being to construct a wax carrying pad so that lateral movement of the wax due to centrifugal action is limited. A still further object is to provide means for vertically adjusting the carriage relative to the floor so that the desired pressure may be applied to the finishing tools.

We attain our objects by means of the constructions hereinafter described, and illustrated in the accompanying drawings in which

Fig. 1 is a vertical section of our carriage showing the finishing tools in elevation;

Fig. 2 a horizontal section of the carriage;

Fig. 3 a vertical section of the brush finishing tool;

Fig. 4 a vertical section of the waxing finishing tool;

Fig. 5 a plan view of the underside of the waxing tool, partly broken away; and

Fig. 6 a sectional detail of the gliders.

1 is a carriage having depending sides and ends, the ends being provided with gliders 2 as hereinafter described. At the sides of the carriage substantially midway between the ends thereof are carried the vertically adjustable wheels 3. These wheels are journalled on slides 4 which are mounted in the guides 5 secured at the inner opposite sides of the carriage. Any suitable means such as set screws 6 may be employed to hold the slides as adjusted so that the carriage may be balanced and run on the wheels, the

gliders only being used to prevent the device from tipping.

In the bearings 7 secured to the carriage are journalled the tubular spindles 8 having the pulleys 9 and 30 secured to their lower ends. At the upper ends of the spindles are secured, by means of pins, the collars 40 to prevent longitudinal movement of the spindles. These pulleys and spindles are driven by a motor 34 as hereinafter described. On the pulleys 9 and 30 are interchangeably carried the floor finishing tools which include a brush 10 and a waxing pad 11.

To polish floors having an uneven surface the machines now on the market depend entirely on the flexibility of the brush bristles. When a brush having flexible bristles is rotated by a motor the bristles spread outwardly until they lie against the back of the brush and thus lose their flexibility. To overcome this objectionable feature and to provide means for carrying the brush so that it will polish an irregular floor we carry the brush in an inverted cup shaped carrier 12 (see Fig. 3). The lower end of the rim 13 of this carrier engages the bristles of the brush to limit their outward spread and this lower end is preferably flared outwardly to prevent the rim cutting the bristles.

The brush is loosely received inside the rim 13 and is driven by means of the laterally extending pins 14 secured to the brush, which pins pass through vertical slots 15 formed in the rim whereby the brush will be permitted to rock relative to its carrier, so that it will adjust itself to polish an uneven or irregular floor. The brush carrier 12 is detachably connected with the pulley 9 in the following manner. A disk 31 suitably secured to the lower side of the pulley is provided with keyhole slots 16 adapted to receive the keys 17 formed integral with the disk 18 secured to the carrier 12. To position the keys 17 relative to their slots 16 a stud 19 concentrically carried on the carrier is adapted to be received in the lower end of the tubular spindle 8. This stud passes through holes formed in the carrier and its disk and is provided intermediate its ends with a shoulder 20 adapted to engage the underside of the carrier, the stud being held in position by means of a

nut engaging the upper side of the disk. The brush 10 is provided with a concentric tapered hole through which the lower end of the stud 19 passes to centrally locate the brush relative to its carrier 12. A coil spring 22 having one end secured between the shoulder 20 and the carrier and the other end engaging the top of the brush 10 yieldingly holds the latter in engagement 10 with the floor.

The waxing pad 11 is carried on a carrier 12^a having a depending rim 13^a on which a wax receptacle 23 is detachably connected by means of the bayonet joints 24, see Fig. 15. 4. This wax receptacle is formed with an open bottom below which is suitably carried the perforated cover 32 of leather or other flexible material. The carrier 12^a is provided with a disk 18 having the keys 17 for 20 detachably connecting the carrier with the pulley 30 in the same manner as the carrier 12 is connected with its pulley 9.

When the wax is placed in a rotatable waxing pad driven by a motor the wax is 25 thrown against the inner peripheral sides of the receptacle due to centrifugal force and the wax passes over the centrally located holes of the pad without passing through them so that the holes near the periphery 30 of the pad are the only ones through which the wax passes. This construction also causes the wax to spread in a lateral direction away from the floor finishing apparatus. To limit the movement of the wax due 35 to centrifugal force and to utilize all the perforations in the cover 32 for the passage of wax therethrough and thus prevent the wax spreading laterally of the waxing device we provide the following means. It 40 will be noted that the perforations formed in the cover 32 are arranged in a plurality of spaced series which are substantially concentrically arranged. In the receptacle 23 is fitted a disk 25 having a plurality of 45 rings 26 secured in any suitable manner to the underside of the disk and arranged concentrically thereof. These rings extend downwardly from the disk and their lower edges are adapted to engage the upper side 50 of the cover 32 to limit the lateral movement of the wax inside the receptacle. The rings are spaced apart so that each ring will be substantially in alinement with the outer edges of the perforations in a series so that 55 all the perforations will be utilized for the passage of wax.

The waxing device is used by detaching the receptacle 23 from its carrier 12^a and then removing the disk 25 with its rings 26 60 from the receptacle. Wax is then filled in on the underside of the disk between the rings 26 and the disk is replaced in the receptacle so that the rings rest on the cover 32. The rings thus form separate annular 65 compartments for the wax. Preferably the

rings 26 are of frusto conical form to tend to force the wax through the perforations in the cover 32. When the receptacle is connected by the carrier 12^a the lower end of a stud 19^a carried by the carrier 12^a engages 70 a resilient cushion 33 fitted within the receptacle on top of the disk 25 and limits the upward movement of these parts.

The motor 34 secured to the upper side of the carriage is provided with a depending 75 spindle on which are secured the pulley 27 and 28, the pulleys being connected by means of endless belts with the pulleys 9 and 30 respectively.

Referring to Fig. 1, it will be noted that 80 the pulleys 27 and 28 are arranged one below the other which necessitates suitable means for taking up the distance between the centres of these pulleys. This is accomplished by securing a distance collar 29 to 85 the underside of the pulley 30 and to this distance collar 29 is secured the disk 31 in which the keyhole slots 16 are formed. With this arrangement the disks 31 on the pulleys 30 and 9 are substantially in horizontal alinement whereby different tools of 90 the same height may be attached thereto.

It will be noted that the bearings 7 are offset longitudinally of the apparatus, (see Fig. 2) so that when two similar finishing 95 tools are being used a greater width of floor will be finished than the width of one of the finishing tools without increasing the resistance of each tool.

To vertically adjust the gliders 2 relative 100 to the carriage and thus vary the pressure on the floor finishing tools we provide the following means. Adjacent the lower edges of the depending ends of the carriage are formed holes through which the screws 35 105 are passed. These screws also pass through suitable notches formed in the upper ends of the gliders 2. The gliders are clamped as adjusted against the depending ends, by means of the metal strips or clamping members 36 in which are threaded the screws 35. Preferably each glider is formed by doubling a strip of felt or rubber on itself and cutting the notch or notches in the free ends thereof. These notches are cut sufficiently 110 deep to permit the strips 36 to clamp the gliders when the latter are lowered relative to the screws 35.

What we claim is:—

1. A floor finishing tool including a rotatable carrier having a depending rim; a brush received within the rim; and pin and slot driving connections between the rim and the brush the said pin and slot connections also being adapted to permit the brush to 120 rock relative to the carrier.

2. A floor finishing tool including a rotatable carrier having a centrally located depending stud; a brush having a hole formed therethrough; and driving connections inde- 125 130

pendent of the stud between the brush and the carrier adapted to permit the brush to rock relative to the carrier, the said hole being adapted to receive the stud to centre 5 the brush relative to the carrier and cut away to permit the brush to rock on the stud.

3. A rotatable floor finishing tool constructed as set forth in claim 1 in which 10 spring means are provided for yieldingly holding the brush in engagement with the floor.

4. In apparatus of the class described the combination of a carrier; a motor secured 15 to the carriage; a floor finishing tool including a rotatable carrier formed as an inverted cup having a depending rim and driven by the said motor; and a brush carried by the carrier, the rim being adapted 20 to engage the bristles of the brush to limit their outward spread.

5. A floor finishing tool including a rotatable carrier having a depending rim provided with a plurality of vertical slots and 25 having its lower edge flared outwardly; and a brush provided with laterally extending pins passing through said slots.

6. A rotatable floor finishing tool constructed as set forth in claim 5 in which the 30 carrier is provided with a centrally located stud and the brush is provided with a hole adapted to receive said stud to centre the brush relative to the carrier and permit it to rock on the stud.

35 7. In apparatus of the class described the combination of a carriage provided with depending sides and ends, the ends being provided with gliders; vertically adjustable wheels centrally located at each side of the carriage; a motor located centrally of the carriage; and floor finishing tools journaled at opposite ends of the carriage and rotated by the motor.

40 8. A rotatable floor finishing tool including a wax carrying receptacle having an open bottom; a perforated waxing pad secured below the receptacle; and means intermediate the periphery and the center of the receptacle for limiting the movement of the wax due to centrifugal action.

45 9. A rotatable floor finishing tool including a wax carrying receptacle having an open bottom; a perforated waxing pad secured below the receptacle; and rings suitably carried within the receptacle to form annular compartments for the wax.

50 10. A rotatable floor finishing tool including a wax carrying receptacle having an open bottom; a perforated waxing pad secured below the receptacle; a disk fitted in the receptacle and having a plurality of spaced rings depending therefrom, the rings being adapted to form annular compartments for the wax.

55 11. A rotatable floor finishing tool includ-

ing a wax carrying receptacle having an open bottom; a perforated waxing pad secured below the receptacle, the perforations being arranged in a plurality of spaced series arranged substantially concentric with 70 the pad; and a plurality of rings suitably supported within the receptacle, each ring being substantially in alinement with the outer edges of the perforations in one of the series.

75 12. A rotatable floor finishing tool constructed as set forth in claim 9 in which the rings are of frusto conical form.

80 13. In apparatus of the class described the combination of a carriage; a motor secured to the carriage and provided with a depending spindle; a pair of pulleys secured to the spindle, one below the other; a pair of spindles journaled on the carriage; a pulley secured to one of the said spindles substantially in alinement with the lower one of the two first mentioned pulleys and provided with a pair of keyhole slots; a pulley secured to the other spindle substantially in alinement with the upper one of the two first mentioned pulleys; a distance collar secured to the underside of the last mentioned pulley and provided with a pair of keyhole slots; and a pair of floor finishing tools, each provided with a pair of keys 90 adapted to be received in either pair of keyhole slots.

95 14. Apparatus of the class described constructed as set forth in claim 13 in which the spindles are tubular and in which the floor finishing tools are provided with upwardly extending studs adapted to be received in the lower ends of the tubular spindles to position the keys relative to the keyhole slots.

100 15. In apparatus of the class described the combination of a carriage provided with depending ends; gliders having openings formed therein; screws passed through the said ends and adapted to pass through the said openings to permit vertical movement of the gliders relative to the carriage; and clamping members adapted to engage the gliders and provided with threaded holes to receive the screws.

115 16. In apparatus of the class described, the combination of a carriage, a vertical motor secured to the carriage centrally thereof on its longitudinal middle line; two floor finishing tools vertically journaled on 110 the carriage and driven by the motor, the journals of said tools being located one forward of the motor and at one side of the said longitudinal middle line and the other behind the motor and at the other side of 120 the said line; and a handle in alinement with the said longitudinal middle line.

125 17. In apparatus of the class described, the combination of a carriage, a vertical motor secured to the carriage centrally 130

thereof on its longitudinal middle line; two floor finishing tools vertically journalled on the carriage and driven by the motor, the journals of said tools being located one forward of the motor and at one side of the said longitudinal middle line and the other behind the motor and at the other side of the said line; a handle in alinement with

the said longitudinal middle line; and a pair of ground wheels journalled on the carriage, one axis lying in a transverse plane in which lies also the axis of the motor.

Signed at Toronto, Canada, this 23rd day of January, 1923.

PHOEBE A. GREEN.
ANDREW W. GREEN.
